UNITED STATES PATENT OFFICE.

CHRISTOPHER COLUMBUS WARREN, OF HATTIESBURG, MISSISSIPPI.

CHURN-OPERATING MECHANISM.

SPECIFICATION forming part of Letters Patent No. 514,636, dated February 18, 1894.

Application filed July 15, 1893. Serial No. 480,659. (No model.)

To all whom it may concern:

Be it known that I, CHRISTOPHER COLUMBUS WARREN, a citizen of the United States, residing at Hattiesburg, in the county of Perry and State of Mississippi, have invented 5 a new and useful Improvement in Churn-Operating Mechanisms, of which the following is a specification:

The invention relates to improvements in 10 churn operating mechanism.

The object of the present invention is to 15 improve the construction of that class of churns having vibrating dashers, and to provide a churn operating mechanism which may be readily secured at the desired elevation to accommodate any height of churn body, and in which the dasher may be readily adjusted in height to suit the contents of the churn body.

20 The invention consists in the construction and novel combination and arrangement of parts hereinafter fully described, illustrated in the accompanying drawings and pointed out in the claim hereto appended.

25 In the drawings—Figure 1 is a perspective view of the operating mechanism of a churn embodying the invention. Fig. 2 is a vertical sectional view.

Like numerals of reference indicate corresponding parts in both figures of the drawings.

30 1 designates a bracket frame having a casing open at its outer end and one side and composed of a back 2, a top and bottom 3 and 35 4, which are secured to the back, and sides 5 and 6 secured to the top and bottom and to the back of the frame. The top, bottom and sides form a box-like casing or frame, and the side 6 extends only a short distance from the back leaving the frame open. The back 2 40 projects above and below the box portion of the frame, and is provided with perforations for the reception of securing devices for fastening the frame to a wall or other suitable 45 support; and the frame may be arranged at any desired elevation to suit the height of the churn body 7 employed.

The top and bottom 3 and 4 of the frame 50 are provided with L-shaped bearing recesses 9 and 10, which are arranged at the open por-

tion of the frame, and which receive a movable dasher shaft 11; and the latter is adjustably secured in the frame by a sheave or drum 11^a, which is provided with a set screw 12 for engaging the dasher-shaft. The drum 11 is 55 arranged within the frame between the top and bottom thereof, and prevents the shaft 11 moving vertically after the same has been adjusted; and the set screw 12 permits the shaft to be raised and lowered to bring a 60 dasher 13 at the desired elevation to suit the quantity of cream being churned. The dasher 13 is provided with an elliptical opening, and is preferably formed integral with the dasher shaft and is capable of effecting a rapid 65 production of butter. The dasher is vibrated or reversely rotated by an operating cord or rope 14, which is centrally fastened to the drum, and which has its ends wound around the same in opposite directions. The ends of the 70 cord or rope 14 are provided with handles 15, which enable the churn to be readily operated.

It will be seen that the churn operating mechanism is simple and comparatively inexpensive in construction, that the bracket frame which carries the dasher mechanism may be readily secured at any desired elevation to suit the size of a churn body, and that the dasher shaft may be adjusted vertically 75 in order to cause the dasher to operate with the greatest advantage on the contents of the churn body.

Changes in the form, proportion and the minor details of construction may be resorted 80 to without departing from the principle or sacrificing any of the advantages of this invention.

What I claim is—

In a churn operating mechanism, the combination of a bracket frame having a horizontal casing with an open side and front and provided at its top and bottom with L-shaped bearing slots, a dasher shaft journaled in the slots and being removable therefrom and vertically adjustable therein, a drum arranged vertically within the casing and extending from the top to the bottom thereof and receiving the dasher shaft and provided with means for clamping the same, whereby it may 95 100

be secured at any adjustment, and an operating cord oppositely arranged on the drum, the latter, the cord and the shaft being readily detachable from the frame by removing the shaft from the bearing slots, substantially as described.

5 In testimony that I claim the foregoing as

my own I have hereto affixed my signature in the presence of two witnesses.

CHRISTOPHER COLUMBUS WARREN.
